UNITED STATES PATENT OFFICE.

CORNELL FLAGSTAD, AND OSCAR A. FLAGSTAD, OF MINNEAPOLIS, MINNESOTA, AS-SIGNORS TO THE FOLDING CRATE AND BOX CO., OF MINNEAPOLIS, MINNESOTA, A CORPORATION.

FOLDING BOX OR CRATE.

Application filed January 13, 1923. Serial No. 612,502.

To all whom it may concern:

Be it known that we, CORNELL FLAGSTAD and OSCAR A. FLAGSTAD, citizens of the United States, residing at Minneapolis, in 5 the county of Hennepin and State of Minnesota, have invented certain new and useful Improvements in Folding Boxes or Crates, of which the following is a specification.

This invention relates to folding boxes or 10 crates and the main object is to provide a practical and efficient construction of collapsible crate or box used for shipping fowl, animals, commodities, or other goods, where it is desired to return the crate to the original 15 shipper in a compact form. The invention consists primarily of certain new and detailed improvements over the structure patented to us under Letters Patent No. 1,264,912, issued May 7th, 1918. Such improvements are described in the following 20 specification, are specifically pointed out in the appended claims, and are clearly illustrated in the accompanying drawings, wherein:

25 Fig. 1 is an end view of the crate, set up.
Fig. 2 is a top view of the crate, set up.
Fig. 3 is an enlarged sectional view, as seen on the line 3—3 in Fig. 2.

30 Fig. 4 is a detail perspective view of a lower inner corner portion of the crate, showing the construction of the hinge plate 19.

35 Fig. 5 is an enlarged sectional view looking upward against one corner portion of the crate cover, or as seen substantially on the line 5—5 in Fig. 3.

Fig. 6 is a perspective view of one of the 40 cover retaining irons 25.

Referring to the drawings more particularly and by reference characters, which characters respectively indicate like parts in the various figures, 8 designates the base 45 of the crate which is hollow, consisting of a bottom 9 and an upstanding rim 10 secured thereon.

The crate consists further of a pair of end sections 11, a pair of side sections 12 and a cover 13. The end sections 11 are hinged, as at 14, to the base, as are also the sections 12 hinged at 15, but the former are hinged at a lower point than the latter so 50 that the sections can be compactly "knocked down" or folded into the base, as described

in our patent above mentioned. The cover 13 is securable either to the top edges of the sections, when set up as shown, or when the 55 crate is knocked down it is securable to the base member so as to hold all the parts in a compact folded unit.

The side and end sections 12 and 11 are 60 provided at their lower ends with hinge butts 16 and 17, respectively, which are secured by hinge pins or pintles 18, to hinge plates 19, one of which is secured in each inner corner of the base 8. Each plate 19 65 is right angular in shape so that when secured to the base member it will serve as an excellent brace for holding the adjacent base rim portions together, and will also insure the proper relative hinge centers for 70 the side and end sections of the crate to swing on. The pintle bearings 20, of the plate 19, are formed by being struck up from the plate (see Fig. 4) so that it is necessary to slot the plate from one set of 75 bearings to the other and in an angular direction, as the respective bearings are at different elevations. In the forming or striking process, however, the edges of the slot are brought together, as indicated by 80 the line 21, so that the bracing strength (above mentioned) of the plate will not be materially weakened.

The base member is also provided with brackets 22 having openings 23 adapted to 85 receive the fingers 24 of plate 25 of the cover, on one side of the crate, and the bolts 26 of the cover, on the other side, when the crate is in a folded position, thus securing the crate as a compact folded or knocked 90 down unit. The brackets 22 are further provided with perforations 22^a to allow the adjacent hinge pintles to be inserted in the bearings 20 after the plate 19 has been secured.

In setting up the crate the cover is first removed and the side and end sections are then respectively raised to vertical positions, in substantially the same manner as described in the above mentioned patent. Said 100 sections are secured together at their upper adjacent corners by catches consisting of corner irons 27, on the side sections 12, and T-head members 28, on the end sections 11, adapted to engage and interlock with the 105 corner irons. The corner irons 27, are

bridged at their inner ends from the vertical to the adjacent horizontal portions of the sections 12, as at 29, and these bridged portions are provided with apertures 30 for receiving the members 24 and 26 of the cover 13, when the crate is set up, in the same manner as the brackets 22 receive said members when the crate is knocked down or folded together.

10 The cover 13 consists primarily of a series of longitudinal strips secured together by cross strips, the ends of the cover resting normally on the end sections 11, when the crate is set up. One side of the cover is provided 15 with the plates 25 having the corrugated securing fingers 24, while the other side is provided with the securing means including the sliding bolts 26.

The bolts 26 are hingedly secured, as at 20 31, to a movable closing strip 32, having a locking device 33 (see Fig. 2). The bolts 26 are slideable and guide in strips 34, and also in the downward projection 35 of a member 36, secured to the cover. A plate 37, 25 to which the bolt 26 is secured at 31, is secured to the underside of the movable strip 32, and is provided with an ear 38 which, when the strip 32 is closed down, engages in a corresponding hole 39 in the member 36, 30 and thus prevents a retraction of the bolts 26 by the strip 32 moving back. When the strip is locked down there is of course no possibility of such a retraction.

It is understood that suitable modifications 35 may be made in the general design and structural details of this invention, provided, however, that such modifications come within the spirit and scope of the appended claims. Having now therefore fully shown 40 and described our invention what we claim is:

1. The combination with a collapsible crate of the character described, of a hinge plate having one end portion formed at 45 right angles to the opposite end portion and integral with the adjacent edge thereof,

hinge bearings formed in said portions by being struck up therefrom.

2. The combination with a collapsible crate of the character described, of a hinge plate having one end portion formed at right angles to and integral with the adjacent edge of the opposite end portion, said end portions having integral strap members bent in to form hinge members. 55

3. The combination in a crate having a base, inwardly folding pairs of side and end sections and a detachable cover, of catches adapted to secure the side and end sections in set up position, said catches consisting of interlocking corner irons secured on the adjacent edges of said sections, the corner irons of one pair of said sections having apertured extensions, fixed fingers on one edge of said cover and movable securing 60 bolts at the opposite edge of said cover, said fingers and bolts being adapted to engage in said apertured corner iron extensions. 65

4. In a crate having a detachable cover, fixed fingers at one edge of said cover for engagement with one side of the crate, bolts slideable at the opposite edge of the cover for engagement with the opposite side of the crate, a pair of plates secured to said cover for guiding said bolts, a lid hingedly secured to said bolts and movable therewith when open, said lid having downwardly projecting ears adapted to engage with said plate when the lid is closed to prevent retraction of said bolts. 70 75

5. In combination with a crate having a detachable cover, a cover securing member consisting of a plate adapted to be fixed at one corner of the cover, said plate having a channeled portion extending laterally therefrom in a crate engaging finger, and flanges formed integral with the plate for engagement with the adjacent edges of the cover. 80 85

In testimony whereof we affix our signatures.

CORNELL FLAGSTAD.
OSCAR A. FLAGSTAD.
